UNITED STATES PATENT OFFICE.

GEORGE MEACOM, OF CHELSEA, ASSIGNOR OF ONE-THIRD TO WILLIAM R. DRIVER, OF BEVERLY, MASSACHUSETTS.

ARMORED VESSEL.

SPECIFICATION forming part of Letters Patent No. 432,061, dated July 15, 1890.

Application filed August 9, 1889. Serial No. 320,243. (No model.)

To all whom it may concern:

Be it known that I, GEORGE MEACOM, a citizen of the United States, and a resident of Chelsea, in the county of Suffolk and State of Massachusetts, have invented new and useful Improvements in Armored Vessels, of which the following, taken in connection with the accompanying drawings, is a specification.

This invention relates to improvements in armored vessels; and it has for its object to increase the strength of the hull, so as to render the vessel invulnerable against the heaviest modern guns now in use or under construction; to prevent oxidation of the exterior of the vessel by the employment of an outer movable shell arranged outside of the armor; to prevent the space between such outer shell and the armor from being filled with water in case it should be penetrated by a shot or by running on rocks, which I accomplish by filling said space with a series of air-tight metal boxes, by which any damage to the outer shell is confined to the locality that is injured without diminishing the buoyancy of the remaining part of the vessel, and to construct the armor with a hard metallic middle portion, preferably made of hardened steel, arranged between outer and inner linings composed of strongly-compressed cotton or other fiber, for the purpose of arresting the penetrating force of projectiles in the most effectual manner; as will hereinafter be more fully shown and described, reference being had to the accompanying drawings, where—

Figure 1 represents a transverse vertical section of my improved armored vessel. Fig. 2 represents a partial horizontal section on the line X X, shown in Fig. 1. Fig. 3 represents a perspective view of a portion of the hull and improved armor. Fig. 4 represents a perspective view of one of the hollow tanks or boxes that are arranged in the space inside of the outer wooden shell of the vessel, and Fig. 5 represents a detail perspective view of the improved armor.

Similar letters refer to similar parts wherever they occur on the different parts of the drawings.

The invention is applicable to ships already finished, although it is preferable to construct them originally according to my design.

I construct my improved vessel with three or more shells or hulls, one within the other and all perfectly water-tight, with intervening spaces between them adapted to contain the air-tight metal tanks or boxes and the improved armor, as will hereinafter be more fully shown and described.

In building the vessel I first lay a regular wooden keel *a*, Fig. 1, to which is secured, as usual, a number of wooden ribs *b b*. To the sides of said wooden ribs I secure by screw-bolts or rivets angle-iron ribs *c c*, extending from the deck to the keel, said angle-iron ribs being shown in Fig. 2. To said angle-iron ribs *c c* is secured by bolts or rivets the metal hull or shell *d*, preferably composed of steel plates of a proper thickness. I then secure to the top of the wooden keel *a a* a steel keelson *e*, preferably made in the form of a T, or two angle-irons riveted together, as shown in Fig. 1. To the steel hull *d*, I now secure a number of steel ribs *f f*, extending from the deck to the keelson and secured in such parts in any suitable manner, as shown in Figs. 1 and 2, said ribs being secured water-tight to the steel hull *d*. These ribs are preferably located opposite the outer wooden ribs *b b*, and are preferably secured by bolts or rivets to the angle-irons *c c* of said wooden ribs, as shown in Fig. 2. The said steel ribs *f f* are made of a double-T section, with flanges on the inner and outer sides, as shown in Fig. 2, and said ribs are preferably made wider at the top than at the bottom, as shown in Fig. 1. The object of said steel ribs is to form a support for the deck-beams and also to form water-tight receptacles for my improved armor, hereinafter to be described. To the inside flanges of the steel ribs *f*, I secure water-tight a steel shell or hull *g*, as shown in Figs. 1, 2, and 3. I now introduce and fasten throughout the ship wooden deck-beams *h h h*, which are arranged parallel with each other at short intervals and at right angles to the keel, as shown in Figs. 1 and 2, which beams serve as a backing for my improved armor and as a means for receiving the concussions and distributing concussions when the vessel is struck by a shot.

After making the ship as above mentioned I cover the outside of the wooden ribs *b b* with planking *i*, which forms the outer water-tight

shell or hull that serves to prevent oxidation of the inner shells, and in putting on said planking I fill the spaces bounded by the said wooden planking *i*, the metal shell *d*, and the 5 wooden ribs *b b* with air-tight tanks or boxes *k*, preferably made of copper or other ductile metal, as shown in the drawings, the object of which is to retain the buoyancy of the vessel in case a hole should be made in the outer 10 shell from any cause. The vessel is now launched and the upper deck secured in place to the upper-deck beam *H*. The upper deck is preferably composed of steel plates *H'*, secured to the deck-beam *H* and covered with 15 the usual wooden deck-planking *H''*, as shown in Fig. 1.

Through the upper deck *H' H''*, I make above each space bounded by the metal shells *d g* and metal ribs *ff* a hatch *H³*, for the introduction of my improved armor into the 20 spaces between said metal shells, which hatches are closed by means of flush covers *H⁴*, composed of wood and metal, after the armor has been put in place. The lower portion 25 of the space between the metal shells *d* and *g*, I fill with blocks of strongly-compressed cocoanut fiber *l* or equivalent material, (shown in Fig. 1,) which filling extends from the keelson *e* to a place below the water-line *W* where 30 the armor-belt commences. At the upper terminus of the compressed-cocoanut-fiber blocks *l*, I secure to the metal shells or hulls *d g* a metal partition *m*, that serves as a support for the improved armor contained in the 35 water-tight compartment bounded by the steel shells *d g* and steel ribs *ff*, as shown in Fig. 1.

My improved armor consists of blocks *n n*, made of chilled iron or other suitable metal, 40 going from stem to stern of the vessel between the middle portions of the shells *d g*, the lowest blocks in the series resting on the metal partition *m*, as shown in Fig. 1. The spaces between the outside of the chilled-iron blocks *n n* and shell *d* are filled with blocks *o o*, made of strongly-compressed cotton or kiar, and the spaces between the inside of said chilled-iron blocks and the shell *g* are filled with blocks *p p*, made of strongly-compressed cocoanut 45 fiber, as shown in the drawings. This my improved armor, although particularly designed for battle-ships, may also be used to advantage for forts and floating batteries, or in any other places where it is desired to resist the destructive action of heavy guns or projectiles.

The improved armor should extend from the deck downward sufficiently to allow the vessel to roll sidewise to its greatest extent 60 without letting the lower portion of the armor rise above the water-line.

Having thus fully described the construction of my invention, I wish to secure by Letters Patent, and claim—

65 1. An armored vessel consisting of an outer wooden shell *i* and an interior metal shell *d*, secured to the ribs of said outer shell, com-

bined with hollow air-tight metallic tanks *k*, arranged in the spaces between such inner and outer shells, substantially as and for the 70 purpose set forth.

2. An armored vessel composed of an outer wooden shell *i*, a metal shell *d*, secured to the former with a space between them, and air-tight metallic tanks *k k*, arranged in such 75 space, combined with an inner metallic shell *g*, metal ribs *ff*, secured water-tight to said metal shells *d g*, and the armor arranged between said metal shells *d g*, said armor consisting of central chilled-iron or other suitable metal blocks *n n*, compressed-cotton blocks *o o*, and compressed-cocoanut-fiber blocks *p p*, substantially as and for the purposes set forth.

3. The improved armor herein described, 85 consisting of compressed blocks of cotton, compressed blocks of cocoanut fiber, and chilled-metal blocks, said blocks of iron being arranged between the blocks of cotton and the blocks of cocoanut fiber, substantially as 90 and for the purpose set forth.

4. The improved armor, as described, consisting of lower blocks *l*, of compressed cocoanut fibers, and upper armor consisting of chilled or other metal blocks *n n*, compressed-cotton blocks *o o*, and compressed-cocoanut-fiber blocks *p p*, all arranged and constructed 95 substantially as and for the purpose set forth.

5. The armored vessel, as described, consisting of the outer wooden shell *i* and wooden ribs *b*, the metal shell *d*, secured to said ribs, the hollow air-tight tanks *k*, arranged between said shells, the inner metal shell *g*, metal ribs *ff*, secured to said metal shells *d g*, and the armor consisting of a series of chilled-metal or other suitable metal blocks, compressed-cotton blocks, and compressed-cocoanut-fiber blocks, all arranged substantially as and for the purpose set forth.

6. The armored vessel, as described, consisting of the outer wooden shell *i* and two or more metal shells *d g*, combined with the hollow air-tight metal tanks *k*, armor *n o p*, composed of metal blocks arranged between blocks of compressed fiber, the metal ribs *ff*, and wooden deck-beams *h h h*, substantially as and for the purpose set forth.

7. In an armored vessel, the metal shells *d g* and metal ribs *ff*, combined with the armor-blocks *n o p*, composed of metal blocks 120 arranged between blocks of compressed fiber, the hatches *H³* in the upper deck, and flush covers *H⁴* for said hatches, substantially as and for the purpose set forth.

8. An armored vessel, as described, consisting of two or more metal shells *d g*, having arranged between them an armor composed of metal blocks placed between blocks of compressed fiber, combined with an outer wooden shell *i*, substantially as and for the 130 purpose set forth.

9. An armored vessel consisting of two or more metal shells *d g* and metal ribs *ff*, secured water-tight to such metal shells and

upper deck, and metal keelson secured to such metal ribs, combined with the horizontal metal partition or armor-support *m*, lower filling *l*, and armor *n o p*, said armor composed of metal blocks arranged between blocks of compressed fiber, substantially as and for the purposes set forth.

In testimony whereof I have signed my

name to this specification, in the presence of two subscribing witnesses, on this 5th day of 10 August, A. D. 1889.

GEORGE MEACOM.
